[57] CLAIM

The ornamental design for a shoe upper, as shown and described.

DESCRIPTION

FIG. 1 is a left side elevational view of a shoe upper showing my new design;

FIG. 2 is a right side elevational view thereof;

FIG. 3 is a top plan view thereof;

FIG. 4 is a front elevational view thereof;

FIG. 5 is a rear elevational view thereof;

FIG. 6 is a left side elevational view of the embodiment of FIG. 1 in a modified position;

FIG. 7 is a right side elevational view of the embodiment of FIG. 2 in a modified position;

FIG. 8 is a top plan view of the embodiment of FIG. 3 in a modified position;

FIG. 9 is a front elevational view of the embodiment of FIG. 4 in a modified position; and,

FIG. 10 is a rear elevational view of the embodiment of FIG. 5 in a modified position.

The broken line showing of a shoe sole in the Figures is environmental only and forms no part of the claimed design.
